NELSON M. BAKER, OF SOUTHBIDGE, MASSACHUSETTS, ASSIGNOR TO AMERICAN OPTICAL COMPANY, OF SOUTHBIDGE, MASSACHUSETTS, A CORPORATION OF MASSACHUSETTS.

OPHTHALMIC MOUNTING.

1,306,514.

Specification of Letters Patent.

Patented June 10, 1919.

Application filed July 24, 1916. Serial No. 110,973.

To all whom it may concern:

Be it known that I, NELSON M. BAKER, a citizen of the United States, residing at Southbridge, in the county of Worcester and State of Massachusetts, have invented certain new and useful Improvements in Ophthalmic Mountings, of which the following is a specification.

This invention relates to improvements in 10 ophthalmic mountings, and has particular reference to an improved process of construction of a fitting for such mounting.

The leading object of the present invention is the provision of a novel manner of 15 constructing a lens clip or like fitting from a single piece of material without the necessity of soldering or otherwise connecting the several parts.

A further object of the invention is the 20 provision of an improved manner of constructing a lens clip from filled material which will insure every exposed portion of the clip being covered with the precious metal and will expose no flat edges and 25 which will consequently eliminate all liability of tarnishing or discoloration of the clip at the edges as is liable to occur with ordinary constructions of lens clips or fittings of filled material.

Other objects and advantages of my improved method of construction for fittings for ophthalmic mountings should be readily apparent by reference to following description taken in connection with the accompanying drawings, and it will be understood that I may make any modifications in the specific details of construction shown and described within the scope of the appended claims without departing from or 30 exceeding the spirit of my invention.

Figure I represents a fragmentary view of the swaged strip from which my clips are made.

Fig. II represents a view of one of the 45 blanks from which my clip is formed.

Fig. III represents a view of the completion of the first operation.

Fig. IV represents a view during the second operation.

Fig. V represents a side elevation showing the clip at the completion of this operation.

Fig. VI represents a view illustrating a further operation.

Fig. VII represents an end view of the 55 clip at the completion of these operations.

Fig. VIII represents a side elevation illustrating the manner of spreading the closed end of the clip.

Fig. IX represents a semi-diagrammatic view illustrating the combined machine for 60 carrying out certain parts of the operation.

Fig. X represents a similar view illustrating one manner in which the clip might be completed.

Fig. XI represents a perspective view of 65 the completed fitting.

In the drawings, in which similar characters of reference are employed to denote corresponding parts, the numeral 1 designates as an entirety a blank adapted for the 70 formation of one of my improved one-piece clips. This blank I have shown as preferably formed from a solid bar of material as indicated in Fig. I, although it will be understood that this bar may be either solid or 75 tubular as may be preferred.

In the form of invention particularly illustrated, however, I have shown the bar from which the blanks 1 are formed as a strip of solid material of sufficient original 80 ductility or sufficiently annealed to render formation thereof by striking or swaging an easy operation, it being understood that the operation in connection with a tubular piece would be the same, the main advantage 85 being readiness of compression or forming in the case of a hollow strip. In any event I first swage or reduce the strip to form a plurality of blanks 1 each comprising if desired a base metal core 2 entirely incased by the precious metal portion 3.

It is to be understood that of course my process is adapted for use in connection with solid gold or other precious metals but 95 is particularly desirable for use in connection with mountings of gold-filled or similar filled material in that by using the process as hereinafter described I am able to maintain the precious metal coating 3 substantially intact and unbroken over the entire finished article, a feature which has been previously pointed out as especially desirable in connection with materials having a base metal core.

As before mentioned, to accomplish this result I form by swaging or striking a series of blanks connected merely by the extremely narrow necks 4, separation being finally effected at the neck 4, leaving a very slight 110

portion of core 2 exposed at each end of the blank. I then preferably cut out or mill one end as at 5 to provide a V-shaped notch, after which I am ready to proceed with the 5 formation of the clip proper.

In the formation of the clip I suitably strike the blank on opposite sides to form a portion substantially H-shape in cross-section as illustrated in Fig. IV, having the 10 central connecting web 6 and the pair of lateral portions or ears 7, the end of the web 6 being slightly inside the termini of the ears 7 on account of the V-shaped notch at 5 just referred to.

15 A form of machine for constructing this portion of the clip is diagrammatically illustrated in Figs. IX and X from which it will be seen that the side striking may be done by the jaw members 8 and 9 engaging the 20 blank at diametrically opposite points, one of said jaws being provided with the extension 10 on which the other jaw may slide, while the jaws are adapted to slide between the second pair of forming jaws or shapers 25 11 and 12 which are just spaced sufficiently to allow of movement of the jaw members 8 and 9 there-between. In use the blank may be dropped downward into the recess between jaws 11 and 12 till the notch 5 rests 30 on the portion 10 as indicated in connection with Fig. VI; when the jaws 8 and 9 may be brought together to strike the material substantially into the shape shown in cross-section in Fig. IV, this striking forming the 35 reduced web 6 and at the same time forcing the side ears 7 outward into the shaping recesses or faces 13 and 14 of the jaws 11 and 12 respectively. At this time the blank will 40 present substantially the appearance indicated in Fig. V. I then preferably level off the end of the web member 6 and continue the formation of the completed clip by striking the upper or outer end of the blank as by the wedgelike hammer 15, indicated in Fig. VIII, this member serving to 45 drive downward the entire blank whereby the web is formed with a flattened shoulder as illustrated in Fig. XI showing the completed article and at the same time the material of the blank is forced tightly against 50 the shaped faces 13 and 14 of the jaw members 11 and 12 and is caused to assume approximately the shape of the inner face of these members. In addition the striking 55 with the wedgelike member 15 spreads the outer end of the blank to produce the laterally extending shoe or strap portions 17 at each side of the clip as indicated in connection with Fig. VIII.

60 It is to be understood that these operations may be performed either sequentially in a single machine, may be separately performed in different machines; may be performed substantially simultaneously by a 65 single operation of the one machine or may

be formed separately and the blank or partially produced article annealed after each operation as may prove most desirable in connection with the handling of different materials or in the formation of different 70 shapes of clips or clips from different weights of material, the essential feature of the invention being the process by which the completed article is produced, broadly speaking.

75 In any event it will ordinarily be found necessary at least after the completion of the operation illustrated in Fig. VIII, to anneal the blank or partially finished article before attempting to completely finish the same. 80 The article having been annealed it is then placed between suitable forming or clamping jaws such as the jaws 8, 9, 11 and 12 previously referred to and is similarly struck at the outer exposed end as by a shaping hammer 18, having the shaped portion 19 to finally shape the outer end of the strap into its desired form and to at the same time additionally force downward and outward the material forming the side ears 7 85 90 to cause them to exactly conform to the inner faces of the jaws and be produced with clean-cut, sharp edges and smooth regular surfaces such as are desired in the finished clips. It will of course be understood 95 that a certain amount of this striking and forming operation may be done by reciprocation of the jaw members 11 and 12 in place of performing the operation entirely by the forcing of the material down thereinto, this 100 being a matter of selection according to the taste of the individual manufacturer or producer of the article.

105 From the foregoing description taken in connection with the drawings the general steps in the process of forming my one-piece lens fitting having the central web, the lateral ears and the strap portions for engaging the edge of a lens should be readily apparent, and it will be seen that in the original blank a slight portion of the base metal is exposed at each end of the blank, that in the formation of the shoe or strap member 17 the general formation thereof is such as 110 to cause a certain portion of the surface material adjacent to the exposed base metal portion to flow over the base metal while at the same time any exposed base metal parts will come at the exact center of the shoe at the point where the remainder of the mounting is soldered or secured thereto so that in the completed article no base metal will be exposed at this point. The only base metal remaining exposed in connection with the entire article is disposed at the V-shaped 115 notch 5, while this material is so disposed that any portion whatever of base metal remaining exposed in the final article will be located only at the end of the web member 6. This web member 6 is adapted 120 125 130

to fit within a slot or the like in a lens and to be retained by a suitable filler, which consequently will be entirely concealed and protected in the completed mounting. It will therefore be apparent from the above that I have provided an improved process of constructing a one-piece fitting for lenses in a simple and efficient manner and in a manner in which all exposed parts and edges in a case of filled material will be thoroughly protected and covered by the original precious metal shell without the necessity for additional plating or the like to cover the same.

15 I claim:

1. The process of forming a one-piece ophthalmic lens fitting, consisting in shaping a blank, and striking the blank to form a central web having integral with each side thereof a lens engaging ear.

2. The process of forming a fitting for an ophthalmic lens, consisting in shaping a blank, striking the sides of the blank to form a member substantially H-shape in cross section, and striking the end of the blank to expand the material into final shape.

3. The process of forming an ophthalmic fitting, consisting in reducing a bar of material to a series of blanks connected by thin necks, separating the blanks, striking one of the blanks at diametrically opposite points to produce a substantially H-shaped piece in cross section, and compressing the sides of the H into desired shape.

4. The process of forming a one-piece 35 clip, consisting in forming a blank of H-shape in cross section, securing the blank between shaping jaws, with a portion projecting beyond the jaws and striking the projecting portion to expand the same and 40 force a portion thereof within the jaws to cause the entire blank to closely conform to the inner shape of the jaws, substantially as described.

5. The process of forming an ophthalmic 45 fitting, including shaping a blank, milling the end of the blank, fitting the milled end over a former, and striking the opposite end of the blank to cause the milled portion thereof to conform to the shape of the 50 former.

6. The process of forming a lens fitting, consisting in striking a blank on opposite sides to form an H-shaped member in cross section, pressing the sides of the H into 55 desired shape, securely holding the blank, with a portion projecting from the clamp, expanding the projecting portion into laterally extending ears, and rounding said expanded portion, substantially as illus- 60 trated.

In testimony whereof I affix my signature in the presence of two witnesses.

NELSON M. BAKER.
